United States Patent Office.

SAMUEL EPLEY, OF McGRAWSVILLE, INDIANA.

Letters Patent No. 96,214, dated October 26, 1869.

IMPROVED TUYERE.

The Schedule referred to in these Letters Patent and making part of the same.

To all whom it may concern:

Be it known that I, SAMUEL EPLEY, of McGrawsville, in the county of Miami, and State of Indiana, have invented a new and useful Improvement in Tuyere-Irons; and I do hereby declare that the following is a full, clear, and exact description thereof, reference being had to the accompanying drawings, and to the letters of reference marked thereon.

Figure 1 represents an elevation of the tuyere;

Figure 2, a vertical section of the same;

Figure 3, a plan view of the lower half of the blast-pipe;

Figure 4, a section taken in line xx of fig. 1, showing the two channels of the blast-pipe; and

Figure 5, a view of the damper.

Like letters denote like parts in the several figures of the drawings.

My invention consists in improvements in tuyere-irons for forges, the several parts of which will be described more fully hereinafter.

To enable those skilled in the art to make and use my invention, I will proceed to describe its construction and operation.

A represents the hearth-plate, which has a circular hole to receive the cylinder B, and flanged ring C. Around this hole, on the under side of the plate, is a rim, a , in which the end of the cylinder is nicely fitted.

Some distance from this rim are two ribs, a' a'' , of against which the upper section of the chamber d' , of the blast-pipe, is held.

B represents a hollow cylinder, the upper end of which fits nicely in the opening of the hearth-plate, to the under side of which it is secured, by means of the flange b . It has an opening in one side, for the admission of the blast-pipe.

B' represents a circular plate or cover, with a handle, b' . It is suspended from the hearth-plate by the standard b'' , on which it revolves. Its upper side is flush with the lower end of the cylinder B, and it is turned under the latter, closing it when the forge is in operation.

C represents a flanged ring, which is inserted in the

opening of the hearth-plate, its flange c resting on the upper end of the cylinder B, and its body extending down in it, to within a short distance of the annular chamber d' , of the blast-pipe. This ring is the bed of the fire.

At c , it has an enlargement, which closes the opening in the side of the cylinder, and fits nicely over the channels d'' and d''' , of the blast-pipe.

D and D' represent the upper and lower halves of the blast-pipe, which are secured together air-tight. Its rectangular chamber d' is secured to the under side of the hearth-plate, while its annular chamber, d'' , is in the hollow cylinder, directly under the lower end of the ring C.

At d , the blast enters the rectangular chamber d' , from which it is distributed in two channels, d'' and d''' , to the annular chamber d'' , from the upper side of which it escapes into the fire.

The annular chamber has the shape of a ring, and its opening is of the same diameter as that of the flanged ring C.

E represents a damper, which is hinged in the rectangular chamber d' , and by which one of the channels leading to the annular chamber may be closed, when only a light blast is required.

Having thus described my invention,

What I claim, and desire to secure by Letters Patent, is—

1. The construction of the air-passage D D', having the tubes d'' and d''' , and annular passage d'' , substantially as and for the purpose set forth.

2. The arrangement of the flanged ring C, and annular air-passage d'' , with reference to the cylinder B, substantially as shown and described.

In testimony whereof, I have signed my name to this specification, in the presence of two subscribing witnesses.

SAMUEL X EPLEY.
